United States Patent

Des. 234,280
Patented Feb. 11, 1975

234,280

CHAIR

Kenji Ekuan, Tokyo, Japan, assignor to France Bed Co.,
Ltd., Tokyo, Japan

Filed Feb. 28, 1973, Ser. No. 336,529

Term of patent 7 years

Int. Cl. D6—01

U.S. Cl. D6—70

FIG. 1

FIG. 4

FIG. 2

FIG. 5

FIG. 3

FIG. 6

FIG. 1 is a top plan view of a chair showing my design;
FIG. 2 is a front elevational view thereof;
FIG. 3 is a bottom plan view thereof;
FIG. 4 is a right side elevational view thereof;
FIG. 5 is a rear elevational view thereof; and
FIG. 6 is a perspective view thereof.

The left side elevational view is a mirror image of FIG. 4 and is omitted.

I claim:

The ornamental design for a chair, as shown and described.
